Primary Examiner—Gary D. Watson[57] **CLAIM**

The ornamental design for an adjustable backrest, as shown and described.

DESCRIPTION

FIG. 1 is a front elevational view of the adjustable backrest of the present invention;

FIG. 2 is a back elevational view of the adjustable backrest of FIG. 1;

FIG. 3 is a left side elevational view of the adjustable backrest of FIG. 1;

FIG. 4 is a right side elevational view of the adjustable backrest of FIG. 1;

FIG. 5 is a top plan view of the adjustable backrest of FIG. 1; and,

FIG. 6 is a bottom plan view of the adjustable backrest of FIG. 1.

The fragmented cross-hatching shown on the cushion member is understood to represent fabric and would be continuous throughout.

FIGS. 5 and 6 have been shown on an enlarged scale with respect to the other views.
